UNITED STATES PATENT OFFICE.

JAMES L. MACINERNEY, OF GRAND RAPIDS, MICHIGAN.

SPRING MAT FOR UPHOLSTERED ARTICLES.

Application filed May 6, 1926. Serial No. 107,018.

The invention relates to spring mats for upholstered articles.

The object of the invention is to improve the construction of spring mats or cushion inserts for automobile seats and other upholstered articles, wherein simplicity of construction and arrangement of the parts, and the maximum economy in cost is combined with efficiency and durability.

10 The invention consists in the novel construction and combinations of devices illustrated in the accompanying drawings and hereinafter described, and will be more fully pointed out in the appended claims.

15 In said drawings:

Figure 1 illustrates my improved mat or cushion, as a whole, in a perspective view, partially broken away.

20 Figure 2 is a longitudinal, sectional view thereof, enlarged, the section being taken in the vertical plane indicated by the dotted line 2—2 on Figure 1.

25 Figure 3 is a transverse, sectional view of the same, enlarged, the section being taken on the vertical plane indicated by the dotted line 3—3 on Figure 1.

Figure 4 is a vertical, sectional view of a detail.

30 Figures 5, 6, 7 and 8 are perspective views of the several parts of fabric, detached, which are employed in the construction of my improved mat or cushion.

35 The cushion, indicated in Figure 1 as a whole by the reference letter A, is composed of a plurality of pocketed sections having a spring S in each pocket. The sections will vary in length and number as may be necessary to conform to the dimension of the completed article in which it is to be used, but 40 for convenience in drawing and description, I have illustrated a six by six cushion, i. e. one using thirty six springs.

45 The fabric used is cut into appropriately sized pieces. The piece shown in Figure 5 is of a dimension to form the bottom 1 and two parallel sides 2, 2, of the cushion. The piece shown in Figure 6 is folded so as to form one end 3 of the mat A, an interior wall 4 and an intermediate portion 5, which 50 latter will constitute a part of the top of the completed cushion A. The piece shown in Figure 7 is L-shaped in cross section, the part 6 constituting a portion of the top of the cushion A and the part 7 constituting 55 an interior wall which will be parallel to the wall 4 when in assembled relation. The

wall 7 of the end section of the cushion will however constitute the end wall of the cushion, opposite the end 3. The piece shown in Figure 8 is folded so as to have a 60 part 8 and two bent ends 9 and 10, the wall 8 constituting a division wall, as will be hereinafter explained. The several parts are secured together by hog rings 11 and by stitching, as illustrated.

65 In constructing the mat or cushion A, the edge 12 of the wall 7 of one strip of fabric is connected by stitches 13 to the edge 14 of the bottom 1, and its end edges 15 sewed to the edges 16 of the side walls 2.

70 A number of the division strips 8, suitably spaced apart, are then sewed in to form a plurality of pockets, the ends 9 being sewed to the bottom 1 and the ends 10 to the top part 6 of the strip, as shown in Figures 1 75 and 3. A spring S is placed in each pocket thus formed.

75 The next strip 6—7 is then placed in position, its wall 7 being parallel to the wall 7 already positioned, closing the spring filled 80 pockets, the lower edge 12 being stitched to the bottom 1. Division strips 8 are similarly positioned in spaced apart relation and sewed at their ends 9 and 10 to the bottom 1 and this second strip top 6, thus forming 85 a second series of pockets into each of which a spring S is placed. The vertical walls 7 of the two strips thus positioned are parallel and the second wall 7 positioned functions as a partition wall closing the first 90 row of pockets and separating the springs in the two adjacent sets of pockets from contact with each other.

95 The hog rings 11, inserted as more clearly shown in Figure 4, clip and secure together the top coils of adjacent springs S, the partition wall 7 and the two top walls 6, it being noted that the free edge of the first laid top wall 6 overlaps the second laid top wall 6.

100 Other sections are similarly laid, pockets formed, springs inserted and hog rings applied, until the cushion is ready for the last row of spring filled pockets. Then the strip shown in Figure 6 is used, the edge 17 of the 105 partition wall 4 being sewed to the bottom 1, spaced apart strips 8 positioned and sewed, the top end 10 being sewed to the top 5, springs S inserted in the pockets, and the bottom edge of wall 3 then sewed at 18 to 110 the side edge 19 of the bottom 1.

Hog rings 11 are used to clip the top coils of

adjacent strips 8, the wall 4, and the top 5 to the overlapping adjacent top 6. The line of stitches which secure the edges 15 to the edges 16 is continued across the top of the cushion A and secures the ends 20 to tops 6 and end 21 of top 5 to the top marginal edge 22 of walls 2 and also secures the end edge 23 of wall 2 to end 24 of wall 3.

The order of assembling the various parts 10 and stitching the parts together, and of applying the hog rings, as herein recited for convenient illustration, may, of course, be varied as the skilled workman may desire, without departing from the essential idea 15 of my invention, which is the use of the few parts described and their assembly into the complete unit A.

The cushion so formed presents a neat and finished appearance, the springs are completely enclosed in pockets by a single web of fabric excepting only where the top 6 and 5 are overlapped and hog ringed as shown in Figure 4, and possesses the advantage of a strong, efficient, durable and very economical construction.

I claim as my invention:

1. A device of the character described consisting of a coiled spring-contained cellular casing, said casing comprising a rectangularly shaped piece of fabric folded to form a bottom and two side walls, an inverted U-shaped fabric strip having its longitudinal margins connected to said bottom and extending from one folded side wall to the other, a plurality of inverted L-shaped pieces of fabric parallel to each other and to said U-shaped piece, one margin of the L-shaped pieces being connected to the bottom fabric, the free margin of one of said L-shaped pieces overlapping the U-shaped strip and the free margins of the other L-shaped pieces overlapping an adjacent L-shaped piece.

2. A device of the character described consisting of a coiled spring-contained cellular casing, said casing comprising a rectangularly shaped piece of fabric folded to form a bottom and two side walls, an inverted U-shaped fabric strip having its longitudinal margins connected to said bottom and extending from one folded side wall to the other, a plurality of inverted L-shaped pieces of fabric parallel to each other and to said U-shaped piece, one margin of the L-shaped pieces being connected to the bottom fabric, the free margin of one of said L-shaped pieces overlapping the U-shaped strip and the free margins of the other L-shaped pieces overlapping an adjacent L-shaped piece, the two side walls being connected to the ends of the U-shaped and L-shaped pieces.

3. A device of the character described consisting of a coiled spring-contained cellular casing, said casing comprising a rectangularly shaped piece of fabric folded to form a bottom and two side walls, an inverted U-shaped fabric strip having its longitudinal margins connected to said bottom and extending from one folded side wall to the other, a plurality of inverted L-shaped pieces of fabric parallel to each other and to said U-shaped piece, one margin of the L-shaped pieces being connected to the bottom fabric, the free margin of one of said L-shaped pieces overlapping the U-shaped strip and the free margins of the other L-shaped pieces overlapping an adjacent L-shaped piece, and short partition strips in said U-shaped and L-shaped pieces.

In testimony that I claim the foregoing as my invention, I affix my signature this 27th day of April, 1926.

JAMES L. MacINERNEY.
